FINGER GUARD

Richard W. Girvin, Jackson Heights, N. Y.

Application March 17, 1939, Serial No. 262,335

6 Claims. (Cl. 132—1)

This invention relates to finger guards and more particularly to finger guards for use in connection with decoration of the finger nails.

Objects

The objects of the invention are to provide a guard which will protect the skin adjoining a finger nail so that the finger nail may be decorated without probability of staining the skin adjacent 10 to the nail; to provide a structure which is readily applied and universal to all fingers; to provide a structure which will remain in place frictionally during use; to avoid injury or discomfort to the user; to enable the structure to be made of one 15 piece of material; to secure simplicity of construction and operation; and to obtain other advantages and results as may be brought out in the following description.

Drawing

Figure 1 is an extended face view of the blank from which the finger guard of the preferred form of the invention is formed;

Figure 2 is a top view of the formed finger 25 guard;

Figure 3 and Figure 4 are sectional views on line 3—3 and 4—4 respectively of Figure 2;

Figure 5 is a longitudinal sectional view similar to Figure 3 and showing a modified construction;

Figure 6 is a sectional view on line 6—6 of Figure 5; and

Figure 7 is a longitudinal sectional view similar to Figures 3 and 5 and showing still another modified construction.

Description

In the specific embodiment of the invention illustrated in said drawing, and with initial allusion to Figures 1 to 4 inclusive, the reference 40 numeral 10 indicates a body portion of material from one end of which is bent a spring tongue 11 and from the side of which as an integral part of the body portion are bent side members 12, 12 with the said tongue lying for most part between 45 said side members but out of contact therefrom. As here shown, the side members project upwardly from the body portion 10 and slope somewhat inwardly toward each other for the major portion of each, and provide narrow lips 13, 13 at their upper edges which are directed toward 50 each other but spaced apart approximately the width of a person's finger nail. Viewing the structure in plan so as to look downwardly through the opening between opposed lips 13, 13, 55 the said tongue 11 will be seen below the open-

ing, said tongue preferably being relatively wide and smooth so as to be comfortable to the user when the finger rests thereupon and likewise to have an appropriate inherent resiliency sufficient to retain the device frictionally upon the finger when applied thereto. As here shown, the inwardly directed lips 13, 13 have their inner edges curled so as to avoid any cutting or raw edge where the device engages the skin at the sides of the user's nail. It will be appreciated that the 10 material employed for constructing the guard may be any desirable material and when constructed of thin resilient sheet metal, the curling of the edges of lips 13, 13 adds no undesirable thickness, the drawing necessarily being considerably ex- 15 aggerated. Actually, the edges in use are thin enough to be quite sharp but not sharp enough to cut the skin.

The preferred construction of Figures 1 to 4 is such that it may be used at either end and 20 the inwardly directed fingers at one end of the device are closer together than at the other end of the device. The end having the lips spaced further apart is readily usable on the larger fingers of a person's hand, whereas the other end 25 with the closer spacing of said lips is usable by the same person on the small finger of the hand. The side walls of the gage being resilient, enable considerable variation of finger nail width to be accommodated by both ends of the device. It 30 may also be pointed out that the structure preferably provides a sloping of the said inwardly directed edges so the space between them progressively widens toward the middle of the gage in plan and also slope with respect to the tongue 35 so the distance from the lips to the tongue narrows progressively toward the middle of the gage as viewed in longitudinal section of Figure 3. The user's finger 14, indicated in dotted lines in Figure 2, may therefore be wedged between the 40 tongue and lips and the slope or taper of the lips will conform to the natural taper of the finger nail so that the lips engage along the side of the finger nail in the hollow of the flesh immediately adjacent the finger nail and thus the entire finger 45 nail will be exposed through the opening between the said lips. The spring pressure on tongue 11 applies adequate resiliency both for enabling the finger to be pushed into place and for frictionally retaining the guard upon the finger when once 50 placed and until positively drawn off again.

It will be understood in use, that the finger with the nail to be decorated is slid into place and the guard remains on the finger without any further effort on the part of the user so the other hand 55

of the user is free to apply the desired decoration. The present practice is to employ a coloring compound which dries quickly and by virtue of my guard, will be kept from getting onto the skin 5 adjacent the nail during application. As soon as the coloring material is applied, the guard can be drawn from the finger without any likelihood of transmitting coloring to the adjacent skin since the guard is to be drawn from the finger in a longitudinal direction. It can then be immediately placed on the next finger and the operation repeated.

If so desired, a guard may be provided of only a single size for all fingers, such as shown in Figures 5 and 6, relying entirely upon the resiliency of the side walls 12' to enable the inturned lips 13' to spread from the necessary opening for the smallest finger to the necessary opening for the largest finger of a person's hand. In this instance, tongue 11' is shown as stamped from the portion of body 10' directly beneath the opening between the fingers rather than formed as an extension of metal beyond the body portion as illustrated in Figure 1. In either event, the tongue is given a position in the formed structure so as to extend between the side walls of the guard and underlie the opening between the nail engaging lips. Both Figures 4 and 6 have been shown in full lines in normal position and the side walls have been shown in dotted line in sprung position which they assume when forced in place upon a finger.

It is furthermore within the scope of the invention to provide other than inherent resiliency 25 of the metal for obtaining the desired pressure of the tongue against the finger. By way of illustration, I have shown in Figure 7 a body portion 15 from the sides of which are bent up side walls 16 having inwardly directed lips 17 corresponding in structure and arrangement to side walls and lips 12 and 13 heretofore described. A tongue 18 separately formed from the body portion 15 is shown extending longitudinally between side walls and movable with respect thereto. Springs 19 are positioned between the body portion 15 and said tongue 18 for pressing the tongue upwardly toward the opening between the opposed lips 17, 17. These springs may be attached at their ends to the tongue and body portion respectively or the tongue otherwise retained assembled with respect to the body portion and side walls and lips. The necessary resiliency for enabling the user's finger to depress the tongue is thus obtained by springs 19, 19 and the device is otherwise the same as to function 50 and as to use, as described in connection with the preceding embodiments.

Obviously other detail changes and modifications may be made in the construction and use of my improved finger guard, and I do not wish to be understood as limiting myself to the precise structures shown or described except as set forth in the following claims when construed in the light of the prior art, it being emphasized

that the present structure is not one for protecting any part of the finger nail nor intended for use in applying any special design on a finger nail, but is primarily a structure for preventing coloring getting onto the skin adjacent a finger nail while the finger nail is being colored.

I claim:

1. A finger guard with open ends having lips for frictionally engaging next the longitudinal edges of finger nails, said guard having a space 10 between said lips upwardly open for exposing the entire finger nail of the finger to which the guard is applied thereby enabling the entire nail to be colored while the guard is in place and the skin protected next the side edges of the nail. 15

2. A finger guard with open ends having lips for frictionally engaging next the longitudinal edges of finger nails, said guard having a space between said lips upwardly open for exposing the entire finger nail of the finger to which the guard is applied thereby enabling the entire nail to be colored while the guard is in place and the skin protected next the side edges of the nail, and resilient means for applying a frictional pressure for retaining the guard in place during use. 25

3. A finger guard with open ends having lips for frictionally engaging next the longitudinal edges of finger nails, said lips providing a wider space therebetween next one end of the guard than at the other end and said lips tapering to 30 be further apart at the middle of the guard than next the ends thereof whereby either end of the guard may be applied to a finger by insertion of the finger longitudinally of the guard from either end thereof and with the nail of the finger 35 exposed between the tapering lips of the guard.

4. A finger guard comprising a body portion having an end extension integral therewith and bent backwardly over the body portion to provide a resilient finger-engaging tongue, said body portion having side members bent upwardly therefrom at opposite sides of said tongue to include the tongue therebetween, said side members having inwardly directed lips at the upper edges thereof. 45

5. A finger guard comprising a body portion having a tongue stamped out of a mid-portion of the body portion between the sides and ends thereof and offset from the body portion for providing a resilient finger-engaging tongue, said body portion having side members bent upwardly therefrom at opposite sides of said tongue to include the tongue therebetween, said side members having inwardly directed lips at the upper edges thereof. 55

6. A finger guard comprising a body portion having side members extending upwardly therefrom and bent inwardly for providing spaced lips at the opposed upper edges thereof, a tongue extending longitudinally of and between said side members, and resilient means between said tongue and body portion for pressing said tongue resiliently in the direction of said lips. 60
